UNITED STATES PATENT OFFICE.

HENRY S. DIMOCK, OF PHELPS, NEW YORK, ASSIGNOR OF ONE-HALF TO
JOSEPH A. STRINGER, OF SAME PLACE.

HITCHING-STRAP.

SPECIFICATION forming part of Letters Patent No. 280,363, dated July 3, 1883.

Application filed May 3, 1883. (No model.)

To all whom it may concern:

Be it known that I, HENRY S. DIMOCK, a citizen of the United States, residing at Phelps, in the county of Ontario and State of New York, have invented a new and useful Hitching-Strap, of which the following is a specification, reference being had to the accompanying drawings.

This invention relates to hitching-straps; and it consists in certain improvements in the construction of the same, which will be hereinafter fully described, and particularly pointed out in the claim.

In the drawings hereto annexed, Figure 1 is a perspective view illustrating the operation of my invention, and Fig. 2 is a perspective view showing the device detached.

The same letters refer to the same parts in both figures.

A in the drawings designates the hitching-strap, the end of which is provided with a permanent loop, B, of sufficient size to be passed over the head of a horse. C is another small loop, arranged to slide upon the loop B and strap A, and having a snap-hook, D, secured thereto by means of rivets, or in any suitable manner.

The operation of my invention will be readily understood by reference to Fig. 1 of the drawings. The loop B is passed over the head of the horse, and the hook D is then snapped in the bridle-ring, thereby retaining the loop C in such a position as to make it impossible for the loop B to come off the head of the horse.

This device is simple, convenient, inexpensive, and safe, it being impossible for the horse to release itself, except by breaking the strap.

I claim as my invention and desire to secure by Letters Patent of the United States—

As an improvement in hitching-straps, the combination, with a strap having at one end a permanent loop adapted to be passed over the head of the horse, of a small loop or ring sliding upon the said hitching-strap and loop, and having a snap-hook adapted to engage one of the bridle-rings, substantially as set forth.

In testimony that I claim the foregoing as my own I have hereto affixed my signature in presence of two witnesses.

HENRY S. DIMOCK.

Witnesses:

J. A. STRINGER,
Wm. P. DIMOCK.
